UNITED STATES PATENT OFFICE.

GEORGE A. REYNOLDS, OF SYRACUSE, NEW YORK.

EXERCISING APPARATUS.

Application filed March 12, 1925. Serial No. 14,959.

This invention relates to certain new and improved exercising apparatus.

The main object of the invention is the provision of a structure utilizable for exercising, rolling, or moving a patient for any desired purpose, as for instance, a reduction in weight.

Other objects and advantages relate to the details of the structure and the parts thereof, all as will more fully appear from the following description, taken in connection with the accompanying drawings, in which:

Figure 1 is a side elevation of the apparatus.

Figure 2 is a front end view of the same taken on line 2—2, Figure 1.

Figure 3 is a section on line 3—3, Figure 2.

Broadly considered, the apparatus consists of a hammock-like structure combined with means for rocking the hammock about a stationary axis to alternately effect an elevating and raising movement of the opposite sides of the hammock.

As here illustrated, the hammock is formed of a base member —1— provided with uprights —2— and —3— at its opposite ends. The uprights —2— and —3— carry at their upper ends pivotally mounted cross-bars numbered —4— and —5— respectively, such pivotal connection being made in any suitable manner, as by means of journals —6— around which the cross-bars —4— and —5— are adapted to be rocked, the pivotal axes of the cross-bars —4— and —5— being in alignment and maintained stationary and being at substantially the center of the bars so that the bars which are preferably of small form and size extend equal distances to opposite sides of the respective uprights —2— and —3—.

The corresponding ends of the cross-bars —4— and —5—, i. e. the ends projecting to the same side of the axis —7— of the cross bars are connected together by means of side rails —7— and —8— respectively, so as to form a substantially rectangular frame rockable about a central longitudinal axis. The side rails —7— and —8— carry the hammock proper, which may, as illustrated, consist of a strip of canvas or other fabric, the opposite side edges of which are connected to the respective side-rails —7— and —8—, and the central portion of which loops down

between the side-rails so as to constitute a carrier for a patient, and within which the patient may safely lie during the rocking of the structure.

A rocking movement of this hammock structure about the pivot journals —6— may be effected in any suitable manner, as for instance by means of pitman —9—, pivotally connected by bolt —10— to the cross-bar —5—, and eccentrically connected by bolt —11— to the rotary gear —12— mounted on the stub shaft —13—, and driven by the relatively small inter-meshing gear —14— mounted upon the armature shaft —15— of an electric motor —16—. The gear ratio may be any desired to effect a predetermined reduction in speed.

It will be obvious that as the gear —14— drives gear —12— the pitman —9— will cause a rocking movement of the rectangular frame consisting of the cross-bars —4— and —5— and side-rails —7— and —8— to thereby alternately raise and lower the opposite edges of the hammock proper or canvas loop —17— to thereby cause a rolling movement alternately in opposite directions of a patient lying within the canvas loop.

It will be apparent that the lowest portion of the fabric loop —17— is always substantially beneath the axis of the hammock frame, and at substantially a uniform elevation, but that the part of the canvas loop —17— that constitutes the lowest portion is constantly varying in accordance with the rocking movement, and as gravity tends to maintain a patient in the lowest portion of the loop, a rolling movement of the patient is caused in accordance with the movement of the covers of the loop.

This movement of the patient caused by this rocking movement of the hammock about a stationary axis has been found to be very efficient in causing a gradual reduction in weight of the patient, and altho I have shown and described a specific structure as illustrative of an embodiment of my invention, I do not desire to restrict myself to the details of form, construction or arrangement of the same, as various changes may be made within the scope of the appended claims.

I claim:

1. An exercising apparatus comprising a pair of pivoted cross-bars, a pair of spaced side bars connected at their opposite ends to

respective cross-bars to form a substantially rectangular structure, a flexible fabric of considerably greater length than the distance between said cross-bars and having one 5 end connected to one side bar and its other end connected to the other side bar, and means for rocking the cross bars to alternately raise and lower the opposite side bars.

- 10 2. In an apparatus of the class described, a pair of spaced uprights, a separate cross-bar pivotally connected to the upper end of each upright, side bars connecting the cross-bars to form a rectangular structure, a loop 15 hammock carried by the side bars, a pitman pivotally connected to one of the side bars

and eccentrically connected to a rotary member, and means for rotating said member.

3. In an apparatus of the class described, a pair of spaced uprights, a separate cross-bar pivotally connected to the upper end of each upright, side bars connecting the cross-bars to form a rectangular structure, a loop hammock carried by the side-bars, a pitman having one of its ends pivotally connected 20 to one of the side bars and its other end connected to a rotary gear, a second gear meshing with the first-named gear, and a motor for driving the second gear.

In witness whereof I have hereunto set 25 my hand this 2nd day of March 1925.

GEORGE A. REYNOLDS.
